BOTTLE HOLDER FOR NURSING BOTTLE

De Witt E. Neibel, Kansas City, Mo., and William R. Carter, Prairie Village, Kans.

Application February 24, 1958, Serial No. 716,999

4 Claims. (Cl. 248—106)

This invention relates to an improvement in bottle holders for nursing a baby, and more particularly to means having positive key holders adapted for a selected position of the nipple of a bottle.

Heretofore holders for nursing bottles were selectively positioned and held by frictional gripping means. If a baby should become sufficiently active to slap or move against the holder, the selected position held by frictional means would often be changed, due to wear or lack of sufficient tightening of the frictional means, resulting in a loss of food for the baby. In some instances a strong person adjusting the frictional holder, would set the screws or clamps too tightly, and a wrench or pair of pliers would often be required, to release the frictional hold for resetting of the bottle holder.

An object of the present improved invention is to provide a means having a positive key holder, for a selected degree of tilt of a bottle gripping member of a bottle holder, the advantage being that the location of the nipple of a supply of milk remains in the same position.

Another object of the present improved invention is to provide a pair of positive key holders with dual controls for a selected degree of tilt of a bottle gripping member of a bottle holder, each key holder being independently releasable, and both key holders requiring simultaneous release to change the degree of tilt of the bottle gripping member. The dual controls are located on opposite sides of the bottle gripping member and are an added safety feature to prevent change of the degree of tilt of the bottle holder should a false or accidental movement be made against one control.

Another object of the present improved invention is to provide a positive key holder between the supporting yoke upright adjustable shank of the bottle holder and the base thereof to hold the bottle gripping member in a selected degree of position against horizontal rotation, thus retaining the same selected position of the nipple of the bottle and bottle gripping member relative to the position of the base thereof.

With these objects in view the invention will be more fully understood from the accompanying drawings, this specification and the scope of the appended claims.

In the drawings:

Figure 1 is a plan view of the improved bottle holder.

Figure 2 is a perspective view of a portion of the yoke and the companion ear, illustrating the keyway in the companion ear, and the latch recesses spaced in both sides of the yoke adapted to match the ends of the keyway.

Figure 3 is a view of a longitudinal elevation of the improved bottle holder.

Figure 4 is a perspective view illustrating one of a pair of keys with a respective lug for attachment to one of a pair of leaf springs.

Figure 5 is a view of an end elevation of the improved bottle holder, illustrating the bottle gripping mem-

2

ber located in a horizontal position. A portion of the yoke and companion ear are broken away to show the interior with the pair of keys latched in a pair of recesses located for the horizontal position. Portions of the base are broken away to save illustrative space.

Figure 6 is a view of a side elevation of Figure 5 with the base removed, and the end portions of the bottle gripping member are broken away.

Figure 7 is a plan view of the divided washer for retaining the adjustable annular grooved nut.

Figure 8 is a view of the bottom of the screw for the yoke illustrating the key, screw keeper and annular grooved nut.

Figure 9 is a plan view of the central portion of the base illustrating the hole for the screw of the yoke. The keyway and recess for the divided washer is illustrated in Figure 7.

The bottle 12 is a conventional type used for feeding a baby and is held by the bottle gripping member 13. The bottle gripping member 13 is made of a spring sheet metal formed in a U section slightly smaller than the bottle as illustrated in Figure 5, and is elongated to the major portion of the length of the bottle 12 as illustrated in Figure 3.

An ear 14 is located along and secured by welding to the longitudinal bottom of the bottle gripping member 13 and is provided with a transverse hole 15 located near the midlength of the bottle gripping member 13. The ear 14 is pivoted to the yoke 16 by pin 17 and is located between the opposed faces 18.

The yoke 16 is formed on the upper end of the screw threaded shank 19. The screw threaded shank 19 has a nut 20 located thereon and has sufficient length to normally match the depth of the upright hole 21 located in the horizontal base 22 when the major depth of the nut 20 is located above the upper surface of the base 22.

A key 23 is secured in the lower portion of the screw threaded shank 19 preferably by the keyway 24 and screw 25. The key 23 projects from one side of the screw threaded shank 19 sufficiently to enter the upright keyway 26. The upright keyway 26 is formed in the base 22 and opens into the full length of the upright hole 21.

The nut 20 has an annular groove 27, formed in the outside surface thereof, adapted to engage the inner edge 28 of the divided washer 29. The divided washer 29 is secured in the recess 30 of the base 22 by screws 31 and retains the fixed elevation of the rotatable nut 20 relative to the top of the base 22.

The lower portion 32, of nut 20, below the annular groove 27, is revolvable in recess 33, and is a stop for the upward movement of key 23.

A keyway 34, is transversely located in the top of the ear 14 adapted to register with a plurality of recesses 35 located in opposed faces of the yoke 16. A pair of keys 36 slidable in opposite end portions of the keyway 34 are adapted to engage a selected pair of recesses 35. The keys 36 are normally held engaged in a selected pair of recesses 35 by means of a pair of spring steel leaves 37 as illustrated in Figure 5. One end of each spring steel leaf 37 is secured to a respective key 36 by means of a lug 38 and rivets 39. The opposite ends 40 of the spring steel leaves 37 are secured to the upper portions 41 of the bottle gripping member 13. Each spring steel leaf 37 has a button 42 thereon.

The recesses 35 are selectively located at spaced intervals to relatively locate the approximate degree of desired slope of the bottle gripping member 13.

In the operation a bottle 12 for a baby is manually pressed in the bottle gripping member 13. The buttons 42 located on opposite sides of the bottle gripping

member 13 are manually and simultaneously pressed to release the pair of keys 36 by means of the spring steel leaves 37 and as illustrated in dash lines in Figure 5. The bottle gripping member is manually tilted to a selected degree relative to a pair of recesses 35 and the pressure is released from the buttons 42 to automatically engage the keys 36 with the selected recesses 35.

The nipple 43 on the bottle 12 is manually located to slope downward by the slope of the gripping member 13. The elevation of the nipple is manually adjusted with the nut 20 turned on screw shank 19. The nipple is prevented from relative rotation with the base 22 by key 23 vertically slidably in upright keyway 26.

The flat side 44 of the base 22 is used for stabilizing the bottle 12 when manually adjusted uprightly for filling with milk or when not used for feeding a baby.

What we claim, as new and desire to secure by Letters Patent, is:

1. A bottle holder adapted for a baby; the bottle holder comprising: a bottle gripping member, an ear, said ear being on said bottle gripping member and projected downwardly therefrom, a yoke, said ear being pivoted in said yoke, a key member, said ear having a keyway located transversely in the top portion thereof, said yoke having a plurality of spaced key recesses located in one opposed face thereof and adapted to selectively register with the keyway in the top portion of said ear, a leaf spring, said leaf spring having one end thereof secured to one side of the bottle gripping member, said leaf spring having the opposite end thereof secured to said key member, said leaf spring being spaced from the bottle gripping member between the secured ends thereof, said key being slidably mounted in the transverse keyway of said ear and normally engaging a selected key recess located in one opposed face of said yoke to positively position the degree of tilt of said bottle gripping member, said leaf spring adapted to release the key member from the selected key recess of the opposed face of the yoke when manual pressure is applied to said leaf spring, a base, and said yoke being secured to the upper portion of said base.

2. A bottle holder as described in claim 1, said base having one flat side, said yoke being located transversely

to the one flat side of said base, said yoke having a shank adapted to be relatively adjustable in height from said base, and said yoke shank being secured against horizontal turning relative to the position of said base.

3. A bottle holder adapted for a baby; the bottle holder comprising: a bottle gripping member, an ear, said ear being on said bottle gripping member and projected downwardly therefrom, a yoke, said ear being pivoted in said yoke, a pair of key members, said ear having a keyway located transversely in the top portion thereof, said yoke having a plurality of spaced key recesses located in opposed faces thereof and adapted to selectively register with the keyway in the top portion of said ear, a pair of leaf springs, said pair of leaf springs having one end of each thereof secured to respective sides of the bottle gripping member, said leaf springs having the opposite ends thereof secured to respective key members, said leaf springs being spaced from the bottle gripping member between the secured ends thereof, said pair of key members being slidably mounted in the transverse keyway of said ear and normally engaging selected opposed key recesses located in opposed faces of said yoke to positively position the degree of tilt of said bottle gripping member, said leaf springs adapted to release the pair of key members from the selected key recesses of the opposed faces of the yoke when manual pressure is applied to both of said leaf springs, a base, and said yoke being secured to the upper portion of said base.

4. A bottle holder as described in claim 1, said base having one flat side, said yoke being located transversely to the one flat side of said base, said yoke having a shank adapted to be relatively adjustable in height from said base, and said yoke shank being secured against horizontal turning relative to the position of said base.
